UNITED STATES PATENT OFFICE.

WILLIAM X. STEVENS, OF EAST BROOKFIELD, MASSACHUSETTS.

IMPROVEMENT IN DOMINOS.

Specification forming part of Letters Patent No. **139,928**, dated June 17, 1873; application filed March 15, 1873.

To all whom it may concern:

Be it known that I, WILLIAM X. STEVENS, of East Brookfield, in the county of Worcester and State of Massachusetts, have invented certain Improvements in Dominos, and in Marking and Ornamenting the Same, of which the following is a specification:

The first part of my invention relates to dominos or cards so shaped and marked on their faces that they may be matched, one with another, at three or more of their sides in playing. The second part of my invention relates to marking and ornamenting dominos by stamping into their faces sheet material of a different color from the blocks, as herein-after set forth.

Figure 1 is a plan of one form, (hexagonal,) of my dominos as used in playing a game I have invented, called "tip-top." Figs. 2, 3, and 4 indicate some of the forms to which my invention may be applied.

These, and pieces of many other forms, both as dominos and cards, marked with any suitable characters, may be made according to my invention, by placing some character on each side or edge of the piece, so that the piece may be matched at three or more sides by similar pieces, forming figures like patch-work. The old style of dominos is marked to be matched only at two ends, so as to increase the forming figure only in length, while my dominos, being marked at three or more sides, match so as to form a figure of both length and breadth. When made as cards, they are printed in the usual way. When made as dominos, they may be made by any usual process; but I make them of wood by shaping strips to the right form and cutting the dominos off from the end of the strip so

that the thickness of the domino is length-wise with the grain. Then they are smoothed and colored, after which comes the marking, wherein consists the second feature of my invention, as follows:

I use a steel stamp with figures raised in relief, corresponding to the markings desired on the face of the domino. I lay a sheet of card-board over the domino, and with the stamp punch the card directly into the domino, the stamp cutting the card against the domino, and bedding the cut pieces of card into the domino, for figuring and ornamentation.

I do not limit myself to the use of wood as a body to be stamped in this manner, or to paper card-board as the figuring material, for there are many materials that may be thus stamped as well as wood, and there is other sheet material than paper that may serve for the marking and ornamentation by thus stamping; but—

What I claim as my invention, and wish to secure by Letters Patent, is—

1. Dominos or cards polygonal in form, having their faces marked near their side edges with characters or figures matchable, one with another, at three or more of the sides so marked, substantially as and for the purpose specified.

2. The method of marking dominos by means of sheet material stamped upon and into their faces, substantially in the manner described and set forth.

WILLIAM X. STEVENS.
